CLAIM

The ornamental design for a telephone set, as shown and described.

DESCRIPTION

FIG. 1 is a front elevation of a telephone showing our new design;

FIG. 2 is a rear elevation thereof;

FIG. 3 is a top plan view thereof;

FIG. 4 is a bottom plan view thereof;

FIG. 5 is a side elevation view from the left thereof;

FIG. 6 is a side elevation view from the right thereof;

FIG. 7 is a front perspective view thereof; and

FIG. 8 is a perspective view in which a hand set is removed from the telephone base.
